UNITED STATES PATENT OFFICE

132,847

DESIGN FOR A POSTER OR SIMILAR ARTICLE

Creed W. Rinehart, Dayton, Ohio

Application January 2, 1942, Serial No. 104,973

Term of patent 3½ years

To all whom it may concern:

Be it known that I, Creed W. Rinehart, a citizen of the United States, residing at Dayton, in the county of Montgomery and State of Ohio, have invented a new, original and ornamental Design for a Poster or Similar Article, of which the following is a specification, reference being had to the accompanying drawing, forming part thereof.

The drawing is a front elevational view of a poster showing my new design.

I claim:

The ornamental design for a poster or similar article substantially as shown.

CREED W. RINEHART.
